UNITED STATES PATENT OFFICE

2,134,786

MOTOR

Ivan P. Haring, Houston, Tex., assignor of two-thirds to Thomas L. Cummings of Harris County, Tex.

Application October 27, 1936, Serial No. 107,791

5 Claims. (Cl. 123—119)

This invention relates to an internal combustion motor.

An object of the invention is to provide novel means for supplying the motive fluid to the motor cylinders.

Another object of the invention is to provide means of the character referred to whereby the motive fluid will be thoroughly broken up and vaporized and delivered in a highly combustible state into the motor cylinders.

It is another object of the invention to provide, in combination with an internal combustion, two cycle, motor an auxiliary compression drum or other receptacle connected with the combustion chambers of the motor, but not with the crankcase, and in which a portion of the pressure from said chambers is stored under compression, said drum being also connected into the fuel feed tank whereby pressure is applied to the fuel in said tank to effect the feeding of the fuel to the intake manifold, said drum being also connected with the carbureting device to the end that the fuel, as fed to carburetor, will be subjected to a blast of the hot compressed vapors delivered from the compression drum.

It is another object of the invention, to provide in an internal combustion, two cycle, motor, novel means for thoroughly scavenging the combustion chambers.

Another object is to provide a two cycle motor having means for readily controlling the speed of the motor and whereby fuel may be fed to the cylinders without dilution from the crankcase lubricants, and without loss of fuel.

With the above and other objects in view, the invention has particular relation to certain novel features of construction, operation and arrangement of parts, an example of which is given in this specification and illustrated in the accompanying drawings, wherein:

Figure 1 shows a plan view of the motor partly in section.

Figure 2 shows a cross sectional view taken on the line 2—2 of Figure 5.

Figure 3 shows a fragmentary sectional view taken on the line 3—3 of Figure 1.

Figure 4 shows a fragmentary end view of the motor showing the auxiliary supply tank and pressure drum.

Figure 5 shows a cross sectional view taken on the line 5—5 of Figure 1, showing the piston in the beginning of the intake stroke.

Figure 6 shows a similar view, showing the piston in an intermediate position.

Figure 7 shows a fragmentary sectional view also taken on the line 5—5 of Figure 1.

Figure 8 shows a cross sectional view of the motor, showing the piston in intermediate position on power stroke, and

Figure 9 shows a cross sectional view of the motor showing the piston in intermediate position on intake stroke.

Referring now more particularly to the drawings wherein like numerals of reference designate similar parts in each of the figures, the numeral 1 designates the motor block as a whole having the cylinders 2, four of said cylinders being shown. The pistons 3 are mounted to reciprocate in the respective cylinders and are connected to the wrists 4 of the crank shaft 5 by means of the usual connecting rods 6. The motor is provided with intake manifolds 7 which are connected into the respective cylinders through the valve seats 8 which are controlled by the intake valves 9. The motor is also provided with the passageways 10 which are connected into the cylinders through the valve seats 11 which are controlled by the valves 12. These valves 9 and 12 are operatively connected with the conventional cam shaft 13 and are so timed that fluid from the pressure drum will be discharged, under high pressure, to force charges of fuel into the respective cylinders after they have been scavenged and the air intake and exhaust ports 30 thereof closed.

The numeral 14 designates an auxiliary fuel supply tank into which the motive fluid is fed from a main supply tank, not shown, through the supply pipe 15. A conventional pump may be 35 employed for feeding the motive fluid into the auxiliary tank 14.

A delivery pipe 16 leads from the auxiliary supply tank 14 and is connected into the valve casing 17 and this valve casing is connected to the cross connection 18 as more clearly shown in Figures 5 and 7. The connection 18 encloses a mixing chamber 19 and leading from the valve casing 17 into this mixing chamber there is a tapering valve seat 20 which is controlled by the needle valve 21 having a threaded connection with the outer end of the casing 17 and has a surrounding stuffing box 22 as shown. A controlling arm 23 is attached to the upper end of the needle valve 21 as more clearly shown in Figure 1.

A manifold pipe 24 is connected into the intake manifolds 7 and leading from the cross 18 and connected into the manifold pipe 24 there is a tubular nipple 25 having a Venturi passageway 26 leading from the mixing chamber 19.

- Adjacent the motor there is a pressure drum 27, one end of which is connected into the top of the auxiliary fuel tank 14 through the elbow 28 which contains a suitable screening element 29. The passageways 10 are connected into the pressure tank 27 through the manifold pipes 30, 30 whereby a portion of the gases on the power stroke under pressure, may be conducted from the combustion chambers into the drum 27 to maintain the required pressure therein. The fuel in the auxiliary tank 14 will accordingly be subjected to the pressure contained in the tank 27 and will be thereby forced through the feed line 18 and through the valve seat 20 into the mixing chamber 19 and will pass thence through the Venturi passageway 26 into the manifold pipe 24 and thence to the cylinders after the air intake and exhaust ports, hereinafter referred to, are closed.
- 20 Leading from the pressure drum 27 there is a nozzle pipe 31 containing the screening element 32. This nozzle pipe terminates in the valve casing 33 in which the turnable valve 34 is seated. The upper end of the valve 34 has an overturned arm 35 which is connected with the arm 23 by means of the cross link 36 pivoted to said respective arms. Any suitable valve controlling device, accessible to the operator, may be employed for shifting the arm 35 and thereby controlling the valves 21 and 34. The outer end of the cross connection 18 is closed by the removable plug 37.

When the motor is stopped and the valves 21, 34 are actuated to closed position, the pressure fluid in the drum 27 will be trapped and maintained under pressure, the valve 21 preventing the feed of the motive fluid from the tank 14. Upon starting the motor the valves 21, 34, should be actuated to open position to permit a resumption of the feed of the motive fluid. Should the pressure in the drum 27 be reduced on account of leakage, while the motor is idle, the pressure will be again restored in the drum 27 while starting the motor, the pistons 3 acting as a pump for that purpose. As the motive fluid is fed through the mixing chamber 19 it will be constantly subjected to a blast of the hot pressure vapor from the drum 27 through the connecting nipple 38, which connects the valve casing 33 with the inner end of the cross connection 18. This nipple 38 has a tapering nozzle passageway 39 therethrough and forms a blast nozzle whereby the pressure vapor will be discharged at high velocity into the mixing chamber 19. The motive fuel will also be fed under pressure and the fuel vaporized in the chamber 19 will be forced through the Venturi passageway 26 and will thereby be further vaporized and will enter the intake manifold pipe 24 and be delivered into the motor cylinders in a highly combustible state and after the cylinders have been scavenged and filled with clean air.

A novel means for scavenging the cylinders has been provided. For this purpose the cylinders are provided with the oppositely arranged ports 40, 41 which are cleared by the corresponding pistons when they reach the limit of their back stroke as is indicated in dotted lines in Figure 9. The ports 40 are inclosed by a manifold 42 shown more clearly in Figure 2. A blow-pipe 43 leads from the fan housing 44 and enters the manifold 42. A blow fan 45 is inclosed within the housing 44 and is operatively connected with and driven by the motor. When the ports 40, 41 are cleared by the corresponding pistons a blast

of air will be driven in through the corresponding port 40 and will strike against the deflector 46 on the inner end of the corresponding piston and will sweep around the corresponding cylinder and discharge through the opposing port 41 and the cylinders will thus be effectively scavenged and filled with clean air which will be trapped therein upon closing of the ports 40, 41. Thereafter the fuel will be forced, under pressure, into the cylinders forming a very combustible and explosive mixture. The screens 29, 33 prevent the escape of carbon or other solid material from the tank 27 into the stream of motive fluid passing to the cylinders.

The drawings and description disclose what is now considered to be a preferred form of the invention, by way of illustration only, while the broad principle of the invention will be defined by the appended claims.

What I claim is:

1. A motor comprising a cylinder, a piston therein, a pressure drum, a conduit leading from the cylinder to the drum, fuel feeding means, an intake pipe leading from the fuel feeding means into the cylinder, valves controlling said conduit and pipe respectively, means for igniting a charge in the cylinder, a conduit leading from the drum to said feeding means, means for controlling the valves whereby, upon firing of the charge in the cylinder, under power stroke, a portion of the pressure fluid will be expelled from the cylinder and be stored in the drum to maintain pressure therein and upon the beginning of the compression stroke fluid will be forced through said pipe from the drum to feed a charge of motive fluid into the cylinder.

2. A motor comprising a cylinder, a piston therein, a container for pressure fluid, said motor having a conduit leading from the cylinder to the container, fuel feeding means, means controlling the amount of fuel delivered to the cylinder, an intake pipe leading from the fuel feeding means into the cylinder through which the fuel is fed, a valve controlling said conduit, means for igniting a charge in the cylinder, means for opening said valve subsequent to the ignition of the charge to admit a portion of the pressure fluid expelled from the cylinder, upon power stroke, into the container to maintain pressure therein, a conduit leading from the container to said feeding means, a valve controlling said intake pipe, means for opening said last mentioned valve, upon beginning of compression stroke, to admit fuel through the intake pipe from the container to feed a charge of motive fuel under pressure into the cylinder.

3. A motor comprising a cylinder having an air admission and an exhaust port, a piston in the cylinder arranged, at the end of power stroke, to clear said ports, a storage drum, said motor having a conduit leading from the cylinder to the drum, a pressure valve for controlling said conduit, fuel feeding means, an intake pipe leading from the fuel feeding means into the cylinder, an intake valve controlling said intake pipe, means for igniting a charge in the cylinder, a conduit leading from the drum to the feeding means, means for opening and closing said last mentioned conduit, means for opening the pressure valve upon firing of a charge in the cylinder, upon power stroke, whereby a portion of the fluid will be expelled from the cylinder and be stored in the drum to maintain pressure therein, means for opening said intake valve upon beginning of a compression stroke whereby the

pressure of the fluid in the drum may be rendered effective to deliver a charge into the cylinder.

4. A motor comprising a cylinder, a piston therein, a storage drum, said motor having a conduit leading from the cylinder to the drum, a valve controlling the conduit, fuel feeding means, an intake pipe leading from said feeding means into the cylinder, an intake valve controlling said intake pipe, means for igniting a charge in the cylinder, means for opening the first mentioned valve, subsequent to firing the charge in the cylinder, upon power stroke, whereby a portion of the pressure fluid will be expelled from the cylinder and be stored in the drum to maintain pressure therein, a conduit leading from the drum to the feeding means, means for opening the intake valve upon beginning of compression stroke to admit fluid under

pressure from the drum, upon beginning of compression stroke, to feed a charge of motive fluid to the cylinder.

5. A motor comprising a cylinder, a piston therein, a pressure drum, a conduit leading from the cylinder to the drum, fuel feeding means, an intake pipe leading from the fuel feeding means into the cylinder, valves controlling said conduit and pipe respectively, a conduit leading from the drum to said feeding means, means for controlling the valves whereby upon firing of a charge in the cylinder, upon power stroke, a portion of the pressure fluid will be expelled from the cylinder and will be stored in the drum to maintain pressure therein and upon the beginning of the compression stroke, fluid will be forced through said pipe from the drum to feed a charge of motive fluid into the cylinder.

IVAN P. HARING.
